SHOWER HOOP FOR PLAY YARDS

Lawrence E. Mayhew and Marian J. Mayhew, both of
16205 Salisbury Road, Independence, Mo.

Filed Oct. 8, 1962, Ser. No. 229,008

7 Claims. (Cl. 4—145)

This invention relates to shower devices, and more particularly to portable shower equipment especially for use in play areas of lawns and the like.

It has long been evident that outdoor shower baths are particularly refreshing in hot weather due to the temperature of the water and evaporation thereof when sprayed into the air for enjoyment of children and their desire to play in the spray from lawn sprinklers and the like. However, heretofore, equipment for such shower baths has been in fixed location or, if portable, merely lawnsprinklers or otherwise improvised devices which create hazards of injury from persons running into or otherwise coming into engagement with the equipment which is usually of metal and relatively immovable. Also, when such devices are located in fixed areas, soggy soil develops, and those devices that are not freely portable for moving to various areas of a yard can result in damage to lawns and the like.

The principal objects of the present invention are to provide improved apparatus for play yard shower baths; to provide a shower bath apparatus that is particularly adapted for use in play yards and the like and including a base member with a spray hoop positioned thereon and normally arranged in upright relation thereto; to provide such a shower device wherein the base member has oppositely inclined ramps upon which a person may move in passing through the spray hoop with said hoop having spray discharge openings for directing sprays generally in the direction of the path of a person moving over the ramps and through the hoop; to provide such a structure wherein the hoop is separably and movably connected to the base whereby the device can be easily assembled and disassembled for shipping and storage with relative small space requirements and when erected the hoop member may be swung toward the base member in response to forces applied against said hoop, as for example a child running into same; to provide such a structure adapted to be made of durable lightweight material such as plastics with all exposed portions formed on contours to reduce possibility of injury by a person coming into contact with the parts thereof; to provide such a shower device wherein the base member has an upwardly opening groove and the hoop member is tubular and has an arcuate portion with spaced ends terminating in laterally spaced downwardly extending legs connected by a horizontal portion adapted to be received in the transverse groove of the base member for pivotal movement relative thereto with means retaining the horizontal portion of the hoop member in frictional engagement with the surfaces of the groove in the base member whereby the hoop member will remain in selected position until forcibly moved; and to provide a portable lightweight shower bath apparatus that is economical to manufacture, easily erected and moved to various locations and that will provide healthy entertainment for persons without danger of injury.

The foregoing objects and advantages of this invention will become apparent from the following description taken in connection with the accompanying drawings wherein are set forth by way of illustration and example certain embodiments of this invention.

FIG. 1 is a perspective view of a shower bath apparatus embodying the features of the present invention.

FIG. 2 is a side elevation of the shower apparatus

2

with broken lines indicating the direction of sprays from the spray hoop.

FIG. 3 is an enlarged partial sectional view through the base and hoop in erected position taken on the line 3—3, FIG. 1.

FIG. 4 is a greatly enlarged partial sectional view through the base and portion of the hoop to illustrate the retaining structure thereof.

FIG. 5 is an enlarged transverse sectional view through the hoop particularly showing the spray openings therein. Referring more in detail to the drawings:

The reference numeral 1 generally designates a portable shower bath apparatus that generally consists of a base member 2 and a shower hoop 3 with a connection 4 for a source of water supply, as for example a hose 5, for delivering water to the hoop 3 to be sprayed therefrom as later described.

The base member may be of any suitable material but is preferably molded of synthetic resin in a structure to provide strength yet lightness in weight. The base member includes laterally spaced side walls 6 with oppositely inclined upper portions connected by oppositely inclined top walls 7 and 8 that extend from ends 9 and 10 respectively upwardly to a center portion 11 having a substantially flat upper surface 12. It is preferred that suitable transverse ribs 13 depend from the inclined top walls 7 and 8 and also from the center portion 11 and have lower surfaces 14 in the same plane as the bottom edges 15 of the side walls and the bottom surfaces 16 at the outer ends of the inclined top walls 7 and 8, all adapted to rest upon the ground or the like in supporting relation to the base and also provide stiffness to the base for added strength.

The hoop member 3 is preferably separably supported on the base member and adapted for swinging movement relative thereto in response to force applied to the hoop member. In the structure illustrated, the central portion 11 of the base member has a thickened portion and there is an upwardly opening groove 17 formed in said central portion, said groove extending transversely of the base member for the entire width thereof and adapted to receive a portion of the hoop member 3 therein. In the structure illustrated, the hoop member is formed of a tubular member 18 having an axial bore 19 with the lower portion of the hoop being a substantially straight horizontal or bottom portion 20 having a cylindrical periphery and received in the groove 17. The ends of the horizontal portion are preferably turned upwardly to form spaced preferably parallel legs 21 and 22 with the upper ends of the legs being connected by an arcuate portion 23 wherein the hoop defines a generally keyhole shape, the hoop having a height from the base whereby when the hoop is upright a child or other person for which the apparatus is adapted can run through the opening in the hoop. It is preferred that the hoop be formed of a single piece of material with the ends of the tubular member connected to a fitting 24 having the connection 4 thereon. It is also preferred that the hoop member be made of a suitable plastic and may be extruded or otherwise formed and then shaped to the desired contour with said plastic having some flexibility and resiliency but sufficient rigidity to normally retain its shape. While the hoop member 3 is shown defining a generally keyhole shape, it is to be understood that other suitable shapes could be used without departing from our invention.

However, it is preferred that the legs 21 and 22 be spaced whereby they have a greater spacing than the width of the base member to permit the hoop member to swing downwardly or be moved to a position wherein the legs 21 and 22 are alongside of the sides 6 of the base member. The hoop member 3 is separable from the base member and when assembled thereon is preferably retained in

frictional engagement therewith whereby the hoop member will remain in selected positions until forcibly moved.

In the structure illustrated, the groove 17 has lesser depth than the diameter of the tubular member 18 and clamp blocks 25 extend across the groove adjacent the sides of the base member and have downwardly opening grooves 26 to engage the upper surface of the horizontal portion 20 of the hoop member. Fastening devices such as bolts 27 are engaged with the clamp members 25 and extend through apertures 28 in the central portion 11 of the base member on opposed sides of the groove 17. It is preferred that some resiliency be arranged in the assembly to maintain a frictional engagement between the clamp members 25, the hoop member and the surface of the groove 17, and springs could be arranged on the fastening devices. However, with the parts being made of synthetic resin having some flexibility, the resiliency is in the material of the base member, hoop member and clamp members whereby nuts such as wing nuts 29 are screwed on threaded ends 30 of the bolts 27 and moved into engagement with the lower surface 31 of the center portion 11 to draw the clamp members 25 into desired engagement with the tubular member portion 20 to hold same in the groove 17.

It is preferred that the entire tubular member have spray discharge openings 32 spaced therealong and arranged to discharge generally on opposite sides of the hoop member. It is preferred that the apertures or spray openings 32 in the arcuate portion 23 be arranged to spray generally toward a point on the axis of the arcuate portion and spaced from the hoop to form opposed cone-shaped sprays as at 33 in FIG. 2. The spray discharge openings in the legs 21 and 22 preferably spray generally horizontally outwardly as at 34 toward the approaches to the ends 9 and 10 of the ramps 7 and 8 respectively. The spray openings in the horizontal portion 20 of the hoop member preferably spray upwardly and outwardly as at 35 in FIG. 2. All of the spray openings in the hoop member are preferably arranged whereby they spray generally toward the approaching path of a person who would move on the ramps and through the hoop.

The structure of the shower bath apparatus is such that it can be shipped substantially knocked down and requires little space for storage. In erecting the apparatus, the clamp members 25 are removed, the hoop member is arranged with the horizontal portion 20 placed in the groove 17, and then the clamp members 25 are arranged wherein the bolts 27 extend through the openings 28 and the clamp members moved down against the horizontal portion 20 of the hoop member 3. The nuts 29 are then tightened to draw the clamp members down and apply a frictional clamping action on the portion 20 of the hoop member to cause said hoop to normally tend to remain in selected position relative to the base member 2. The shower bath can then be easily carried to a desired place of use, the hoop member swung to an upright position as illustrated in FIG. 1, and the connection 4 connected to a hose 5. The water can then be turned on and the spray will provide enjoyment as well as cool refreshing entertainment. The upper surfaces of the ramps 7 and 8 preferably have grooves 36 extending transversely of the ramps or otherwise provided with anti-skid portions to reduce possibility of a person slipping thereon. Edges are rounded or contoured to eliminate any sharp edges or portions that could tend to cut or otherwise injure a person. If a person should run into the hoop, it would swing downwardly and the movement thereof would reduce the force of the impact of the person, thereby substantially eliminating possibility of injury through contact of the person with parts of the apparatus.

It is to be understood that while we have illustrated and described one form of our invention, it is not to be limited to the specific form or arrangement of parts herein described and shown except insofar as such limitations are included in the claims.

What we claim and desire to secure by Letters Patent is:

1. A portable play yard shower bath device comprising,
  - (a) a base,
  - (b) a tubular hoop member having a bottom portion with ends extending outwardly of said base and terminating at its ends in upwardly extending connected side members,
  - (c) means pivotally mounting the bottom portion of the hoop member on the base whereby said side members are outwardly of the base permitting selective swinging movement of said hoop member toward the base, said pivotally mounting means having engagement with said bottom portion to normally retain the hoop in selected position,
  - (d) said hoop member having a water supply connection thereto,
  - (e) and spray discharge openings spaced along the length of said hoop member and arranged to spray water generally toward a line normal to said hoop member.
2. A portable play yard shower bath device comprising,
  - (a) a base having a center portion and downwardly inclined ramp portions extending therefrom,
  - (b) a tubular hoop member having a bottom portion with ends extending from the base and terminating at said ends in upwardly extending connected side members,
  - (c) means pivotally mounting the bottom portion of the hoop member on a horizontal axis transversely of the central portion of the base whereby the side members are outwardly of the base member permitting selective swinging movement of said hoop member toward said base, said pivotally mounting means having engagement with said bottom portion to normally retain the hoop in selected position,
  - (d) said hoop member having a water supply connection thereto,
  - (e) and spray discharge openings spaced along the length of said hoop member and arranged to spray water generally toward a line normal to said hoop member.
3. A portable play yard shower bath device as specified in claim 2 wherein the ramp portions have grooved upper faces to provide anti-skid surfaces thereon.
4. A portable play yard shower bath device comprising,
  - (a) a base having a center portion and downwardly inclined ramp portions extending therefrom,
  - (b) a tubular hoop member having a horizontal portion terminating at its ends in upwardly extending connected side members,
  - (c) means pivotally mounting the horizontal portion of the hoop member on the central portion of the base transversely of the direction of the ramps with the side members and the base associated to permit selective swinging movement of said hoop member toward the ramps, said pivotally mounting means having engagement with said bottom portion to normally retain the hoop in selected position,
  - (d) said hoop member having a water supply connection thereto,
  - (e) and spray discharge openings spaced along the length of said hoop member and arranged to spray water generally in the direction of the path over the ramps.
5. A portable play yard shower bath device as specified in claim 4 wherein the side members of the hoop member are spaced outwardly from sides of the base member.
6. A portable play yard shower bath device comprising,
  - (a) a base having a center portion and downwardly inclined ramp portions extending therefrom,
  - (b) a tubular hoop member having a horizontal portion extending transversely of the base with ends outwardly from the sides of the base member, said hoop member having sides extending from the ends

- of the horizontal portion with said sides connected by an arcuate portion spaced upwardly from the base member to define an opening through which a person may pass in moving over the ramps, 5
- (c) clamp members on the base member in engagement with the horizontal portion of the hoop member and cooperating with the base member to pivotally mount said hoop member for swinging movement about a horizontal portion axis, 10
- (d) means connected to said base and clamp members to tighten said clamp members against said hoop portion to resist swinging movement thereof and thereby retain same in selected position, 15
- (e) and means in a side portion of the hoop member for connection with a source of water supply, 15
- (f) said hoop member having spray discharge openings spaced along the length thereof and arranged to spray water generally in the direction of the path over said ramps.
7. A portable play yard shower bath device comprising, 20
- (a) a base having a center portion and downwardly inclined ramp portions extending therefrom,
- (b) an upwardly opening groove in said central portion of the base and extending transversely thereof,
- (c) a tubular hoop member having a horizontal portion positioned in the upwardly opening groove in the center portion of the base member, said horizontal portion of the hoop member having ends extending outwardly of said groove in the base member and terminating in side portions extending therefrom and 30 connected by an arcuate portion spaced upwardly

- from the base member to define an opening through which a person may pass in moving over the ramps,
- (d) clamp members on the base member extending across the groove therein in engagement with the horizontal portion of the hoop member in said groove and cooperating with said base member to pivotally mount the hoop member for swinging movement about a horizontal portion axis,
- (e) means connected to said base and clamp members to tighten said clamp members against said horizontal portion of the hoop portion to frictionally retain same in selected position and permit swinging movement of the hoop member when struck or forced toward the ramp portions,
- (f) and means in a side portion of the hoop member for connection with a source of water supply,
- (g) said hoop member having spray discharge openings spaced along the length thereof and arranged to spray water generally in the direction of the path over said ramps.
